UNITED STATES PATENT OFFICE

107,409

DESIGN FOR A TOBACCO ASH RECEPTACLE

Talbert M. Dick and Maurice J. Fletcher, Des Moines, Iowa

Application April 27, 1937, Serial No. 69,002

Term of patent 14 years

To all whom it may concern:

Be it known that we, Talbert M. Dick and Maurice J. Fletcher, citizens of the United States, residing in Des Moines, in the county of Polk and State of Iowa, have invented a new, original, and ornamental Design for a Tobacco Ash Receptacle, of which the following is a specification, reference being had to the accompanying drawing, forming a part thereof:

Fig. 1 is a perspective view of a tobacco ash receptacle showing our new design; and
Fig. 2 is a top plan view thereof.

We claim:
The ornamental design for a tobacco ash receptacle substantially as shown.

TALBERT M. DICK.
MAURICE J. FLETCHER.
